UNITED STATES PATENT OFFICE.

JACOB S. SAMMONS, OF NEW YORK, N.Y.

SASH-FASTENER.

SPECIFICATION forming part of Letters Patent No. 271,367, dated January 30, 1883.

Application filed June 12, 1882. (No model.)

To all whom it may concern:

Be it known that I, JACOB S. SAMMONS, of the city and State of New York, have invented an Improvement in Sash Locks and Supports, 5 of which the following is a specification.

My improvement is especially intended for use on railway-car windows, but may be used elsewhere. The lock is made of a hanging lever hinged at the top, and provided with a 10 stop to limit the outward movement and with a spring to press the lower end from the sash. The lower end of this lever forms the lifter, and there are stops upon the frame, receiving a latch projection at one edge of the lever. The 15 lock is disconnected by pressing the lever toward the sash in the act of raising or lowering the window.

In the drawings, Figure 1 is an elevation of the sash-lock. Fig. 2 is a plan of the same, 20 and Fig. 3 is a vertical section at the line xx .

The sash a and window frame or casing b are of any desired character. The plate c is secured to the sash by screws d , and at its upper end is a hinge, e , by which the hanging lever f is attached. This lever is only allowed 25 a limited swinging motion in consequence of the portion 2 of the lever above the hinge-pin forming a stop against the sash, and the parts 3 of the hinge also forming stops. The lever f may be pressed toward the plate c , against 30 the action of the folded or helical spring h ; but said spring can only swing the lever outwardly to the extent permitted by the stops.

At the bottom of the lever f there is a bow or finger piece, k , by means of which the lock can 35 be availed of as a lifter in raising or lowering the sash a . At one edge of the hanging lever f there is a latch-piece, l , that projects toward the window-frame or the stop-bead upon such frame, and upon the frame b or stop-bead there 40 is a catch, m , formed as a notched block, projecting from the surface sufficiently to allow the latch to catch in the notch or against the block as the sash is raised, and thereby support the sash or lock it at any desired place. 45 The spring causes the lower end of the hanging lever to project outwardly and to engage with the catch m , and this spring yields as the fingers are applied to the lock to unlatch the same, and raise or lower the window. There 50 may be one or more catches upon the window-frame, as shown at o , for the latch l to engage with in supporting the sash.

I claim as my invention—

The combination, in a sash-lock, of the plate 55 c , adapted to be screwed to the sash, the hanging lever f , and stop-hinge for uniting the lever to the plate, the spring h , latch l , projecting at the edge of the lever, and the catch m upon the casing, substantially as specified. 60

Signed by me this 9th day of June, A. D. 1882.

JACOB S. SAMMONS.
